Martin Frisch, New York, N. Y., assignor to Foster Wheeler Corporation, New York, N. Y., a corporation of New York

Application July 31, 1940, Serial No. 348,793

20 Claims. (Cl. 122—240)

This invention relates to fluid heaters including vapor generators, and more particularly pertains to steam generators of the type having a setting or the like which is divided by one or more vertical division walls or partitions to provide the generator with two or more separate furnaces adapted to be independently fired and to operate in parallel. In furnace arrangements of this kind, inner surfaces of the walls of the furnaces ordinarily are lined with heat absorbing means such as water wall tubes, and some of the wall surface of one or more of the furnaces may contain radiant heat superheater tubes. The division wall between adjacent furnaces frequently includes two closely spaced parallel rows or groups of tubes, which are secured together by common tie members, and refractory material is disposed in the space between the rows, the arrangement being such that each row of tubes will be directly exposed to the products of combustion produced in only one of the furnaces, and the heating gases will flow through the two furnace chambers in separate paths. When the furnaces are fired unequally, those tubes lining the wall surface of the furnace which is more intensely fired, will expand more than the tubes on the walls of the furnace which is less intensely fired, so that there will be relative movement between the tube rows due to the different furnace temperatures.

The present invention provides supporting means for steam generator furnace division walls having fluid cooling tubes associated therewith, which will support the tubes adequately under all operating conditions and will permit relative movement between rows of these tubes as required, without distortion or other movement thereof.

The invention will be understood from the following description when considered in connection with the accompanying drawings forming a part thereof, and in which:

Fig. 1 is a partial vertical sectional view of one form of steam generator embodying the invention;

Fig. 2 is an enlarged partial vertical sectional view of part of the generator shown in Fig. 1;

Fig. 3 is a vertical sectional view taken on line 3—3 of Fig. 2;

Fig. 4 is an enlarged vertical elevational view of a detail of the generator;

Fig. 5 is a transverse sectional view taken on line 5—5 of Fig. 4;

Fig. 6 is a vertical elevational view taken on line 6—6 of Fig. 2;

Fig. 7 is a sectional view taken on line 7—7 of Fig. 2;

Fig. 8 is an isometric view of part of the generator;

Fig. 9 is a vertical sectional view taken substantially on line 9—9 of Fig. 8, and

Fig. 10 is a transverse sectional view taken on line 10—10 of Figs. 2 and 9.

5 Like characters of reference refer to the same parts in the several views.

Referring to the drawings, particularly Fig. 1, reference character 10 designates generally a steam generator having a setting which includes 10 a front wall 11, a rear wall not shown, and side walls 12 and 13. Midway between the side walls is a vertical division wall which comprises two spaced rows or groups of vertical tubes 14 and 15 and refractory material 16 built up between the rows of tubes. This division wall extends across the setting from the front wall to the rear wall, and provides two separate furnace chambers 17 and 18, which are independently fired by fuel burners 19 and 20 respectively, disposed in front wall 11. 20 Groups of closely spaced water wall tubes 21 and 22 which are connected at their upper ends to headers 23 and 24, and at their lower ends to headers 25 and 26 respectively, line the front wall, and similar groups of water wall tubes not shown, line the rear wall of the setting. The side wall 12 is lined with water wall tubes 27 which are connected to upper and lower headers 28 and 29 respectively, and are connected into the circulatory system of the generator. The 30 side wall 13 is lined with radiant heat absorbing superheater tubes 30 which are alternately connected at their upper ends to inlet and outlet headers 31 and 32 respectively, and at their lower ends to a return header 33. The groups of water wall tubes 21, 22 and 27, and the superheater tubes 30, are secured to the respective setting walls by tie back members 34 which form no part of the present invention and need not be described in detail. In addition to the water wall tubes 21 and 22, another group of shorter water wall tubes 35 line that part of the front setting wall which is adjacent the division wall, and are suitably connected into the circulatory system. A similar group of tubes not shown, is disposed 40 in the rear wall of the setting. Any suitable means are employed to secure the water wall tubes in position and in such manner that they may expand and contract with respect to the wall to which they are attached.

45 In the form shown, the upper ends of the division wall tubes 14 and 15 are connected to a drum 36 which is suitably supported on or from the setting and which serves to support or suspend these tubes together with the refractory material 16 which is inserted between them. At their lower ends the tubes 14 and 15 are connected to headers 37 and 38 respectively. The lower portions of each of the side walls of the 55 furnaces 17 and 18 are inclined inwardly in such 60

a way as to provide each furnace with a water cooled hopper bottom.

As clearly illustrated in Figs. 2, 4, 5 and 6, the two rows of the division wall tubes are secured to each other in the desired spaced relationship by means disposed between the tube rows. Such means includes tie members 41 which are supported on upper lugs 38 and lower lugs 40 which are welded to the tubes 15 and 14 respectively in spaced relationship. The tie members 41 are provided with spaced apertures in alignment with the tubes, and each tie member is of such length as to extend transversely of a plurality of tubes. The apertures in the upper and lower lugs are in axial alignment with each other, and are adapted as are the apertures in the tie members to freely receive pins 42, which are provided with heads 43 to hold the pins in place. This securing means will permit relative vertical movement between the tubes 14 and 15, and will maintain the tubes of each row and the two rows in proper spaced relationship.

Below the vertical portion of the division wall, the groups of tubes 14 and 15 are oppositely inclined to form walls for the hopper bottoms of the adjacent furnaces. Adjacent the hopper discharge point of each furnace, the tubes of each group are bent to extend horizontally in opposite directions towards the center line of the setting before entering the headers 37 and 38 respectively. These headers are carried by a plurality of separate spring supports, each of which includes a spring 44 housed in a casing 45, and which rests on a foundation 46. Between the headers and the springs 44 are saddles or brackets 47, and between the latter and the upper end of each spring is a transverse plate 48 (Fig. 3). Extending between the ends of each plate 48, and lugs 49 which are fixed to the walls of the casings 45, are rods 50 having fixed thereto upper and lower fixed stops 51 and 52 and which are secured at their upper ends to the plates 48. The arrangement is such, that as the springs are depressed or as they expand in response to vertical movement of the headers 37 and 38, the rods 50 will slide through apertures 53 in the lugs 49 and the amount of this vertical movement is controlled and limited by the stops 51 and 52 on the rods 50.

Immediately above the headers 37 and 38, the oppositely inclined hopper sections of the division wall tubes and the refractory portions 54 and 55 of the hopper walls are carried by a steel supporting structure, which as viewed in Figs. 1 and 2, is of a generally triangular shape. Referring particularly to Figs. 2, 3 and 10, gusset plates 56 and 57 which form the apex of this structure extend the length of the setting and are bolted together, the bolt holes in the plate 56 being elongated to permit limited relative movement between the plates vertically. A woven asbestos gasket 57' separates the plates 56 and 57. A plurality of angle members 58 and 59 (Fig. 10) are secured to the plate 56 and a plurality of similar angle members 60 and 61 are secured to the plates 57. The angles 58 and 59 support a casing section 62, while the angles 60 and 61 support casing section 63. The refractory portions 54 and 55 of the hopper walls are enclosed between the casing sections 62 and 63 respectively and the tubes. The angle members 58 and 59 have secured to their lower ends, a member 64 which is connected to a member 65 which rests upon and is connected to the header 37. The angle members 60 and 61 are similarly connected to

members 66 and 67 and the header 38. The upper portion of the casing section 62 extends parallel with the inclined portions of the tubes 14 and the lower portion extends vertically downward to the foundation of the setting. The tubes 14 pass through the casing as indicated at 68 and 69, suitable means being provided to permit relative movement of the tubes and the casing at these points. The casing section 63 and the tubes 15 are similarly arranged. A plurality of horizontal tie members 70 extend between the lower ends of the angle members 58, 59 and 60, 61. The tie members are secured by pins at their ends to the angle members by brackets 71, a pin and slot being utilized at one end of each tie member to permit limited relative movement with respect to one group of angle members.

The greater part of the weight of the refractory portion of the division wall and the casing structure described is supported by two heavy parallel, fixed beams or girders 72 and 73, which extend longitudinally of the setting for the length thereof. Extending between the beams and transversely thereto are a plurality of pairs of channel members 74 which rest on the lower flanges 75 and 76 respectively of the beams. Supported by the channel members are a plurality of spring supports, which are somewhat similar to the spring supports described in connection with the headers 37 and 38. These spring supports have a circular bottom plate 77 (Fig. 3) in which is a centrally disposed aperture 78, and a rod 79 which slides freely in this aperture and extends vertically through a spring 80 and through an upper plate 81 which rests on the upper end of the spring. A stop 82 carried by the rod bears against the upper face of plate 81, and the upper end of the rod is secured between a pair of channel members 84 by a pin 83 which passes through an aperture in the rod or in an extension thereof. This connection is so arranged that the channel members 84 may oscillate about the pin 83 within the limits permitted by the entire structure. Otherwise the structure and operation of these spring supports are similar to those previously described for the support of the headers 37 and 38. The channel members 84 extend transversely between the casing angle members 58, 59 and 60, 61 to which they are connected at their ends by pins 85 (Fig. 7) in such manner that the members 84 may move in vertical planes to a limited extent in either a clockwise or counter-clockwise direction, and any such movement will be against the action of the spring supports.

Roller bearing means are provided to permit vertical movement of the casing sections with respect to the fixed beams 72 and 73. Secured to the upper flanges 86 of the beam 72 is a longitudinally extending angle member 88, and secured to the upper flange 87 of the beam 73 is a similar angle member 89. Adjacent the angles 88 and 89 and attached to the inclined casing angle members 58, 59 and 60, 61 are brackets 90 and 91 respectively. Between the brackets 90 and the member 88, and in contact therewith, are rollers 92. Similar rollers 93 are disposed between the bracket 91 and member 89. Suitable means are provided to confine the rollers 92 and 93 to their bearing surfaces. Fixed to the lower portions of the casing sections 62 and 73 and to the tie members 70, are a plurality of brackets 94 and 95 respectively. Fixed to the brackets 94 or to other parts of the casing section 62, is a longitudinally extending beam 96, and a beam 97

is similarly arranged with respect to the brackets 85 or the casing section 83. Between the inner flange 88 of beam 86 and the beam 72 are a plurality of roller guide brackets 89 within which are rollers 100. Between inner flange 101 of beam 81 and beam 73 are similarly disposed a plurality of roller guide brackets 102 which house rollers 103. It will be apparent that this roller bearing arrangement will permit vertical movement of either or both of the inner hopper walls with respect to the supporting means therefor upon expansion and contraction of the division and hopper wall tubes.

In the hopper walls adjacent the gusset plates 86 and 87, tube securing means are employed which permit relative movement between the tubes 14 and 15, the adjacent refractory portions 84 and 85 of the hopper walls, and the steel casing sections 62 and 63 respectively. As clearly shown in Figs. 8, 9 and 10 of the drawings, rectangular plates or lugs 104 are welded to the peripheries of the tubes at spaced points along the wall sides thereof. These plates are received within spaces 105 between closely spaced hollow blocks or backing members 106 which are T-shaped and have solid projections 107 that are securely locked between the flanges of opposed channels 108 and 109. The lower channel 109 of each receiving means is supported by an angle member 110 which is secured by bolts 111 to the casing section and the upper channel 108 rests upon the projections 107 and upon a plate 112 which rests upon the angle member 110 and the casing section. The channels 108 and 109 and the angle members 110 extend transversely of the tubes for the length of the furnace setting. A plate 113 covers the joints between the lugs 104, the members 106 and the upper angle member 108. The securing means just described is utilized at the upper portion of each hopper bottom on both sides thereof. Similar securing means are employed at the lower portions of the hopper bottoms on both sides thereof, the only essential difference being that the angle member 110 is not used, but the lower channel 108 rests upon the refractory.

In operation, the division wall tubes 14 and 15, including the lower portions of these tubes which extend along the inner vertically inclined walls forming the hopper bottoms of the furnace, will expand and contract with variations in temperature in the furnaces. Where equal or substantially equal temperatures prevail in both furnaces, the division wall and hopper bottom tubes will expand equally and will result in downward movement which is absorbed by the spring supports 80 and 44. Upon contraction, the reverse action will take place. In the event furnace 17 is fired at a greater intensity than furnace 18, the division wall tubes 14 will absorb more heat than the division wall tubes 15, in consequence of which there will be a greater expansion of tubes 14 than tubes 15. As a result, channel members 84 will be moved downwardly against the action of springs 80, but as viewed in Fig. 2, the channels 84 will have a further counter-clockwise movement and will assume a horizontally inclined position. Also the header 37 will move downwardly farther than the header 38. Upon contraction, the reverse movements will occur. In the event furnace 18 is fired at a greater intensity than furnace 17, tubes 15 including their lower portions which extend along the hopper bottom of the furnace, will move downwardly a greater distance than the tubes 14. In con-

sequence, the channels 84 will move downwardly and additionally these channels will move in a clockwise direction so that eventually they assume a horizontally inclined position. At the same time header 38 will move downwardly more than header 37. When the furnaces are shut down, reverse movements will take place.

From the foregoing it will be perceived that with the present invention the division wall tubes including their lower portions, will expand and contract pursuant to temperature conditions in the furnace, and that these division wall tubes may move together or relatively to each other either in expansion or in contraction, or in expansion of one group of tubes with contraction of the other group, or vice versa. Moreover, the tubes are adequately anchored so that they retain their positions irrespective of expansions and contractions.

Although the invention has been disclosed as applied to steam generators, it may be employed with vapor generators generally or in fluid heating apparatus. Moreover, the invention is applicable to furnaces having bottoms other than the hopper bottom type illustrated. It will be understood that changes may be made in the form, location and relative arrangement of the various parts of the apparatus disclosed herein without departing from the principles of the invention which is not to be limited excepting by the scope of the appended claims.

What is claimed is:

1. Fluid heating apparatus comprising a setting, fluid heating tubes in the setting, a plurality of furnaces in the setting, means for firing each furnace, means for separating the furnaces including rows of fluid conducting tubes, means for securing said tubes of one furnace to said tubes of the adjacent furnace in such a manner that the tubes can move axially relative to each other, and means for supporting said separating means at least in part adjacent the lower end thereof, said last mentioned means being constructed and arranged to permit relative movement of the tubes of said rows resulting from expansion and contraction caused by different operating temperatures in said furnaces.

2. Fluid heating apparatus comprising a setting, fluid heating tubes in the setting, a plurality of furnaces in the setting, means for firing each furnace, a division wall between adjacent furnaces, fluid conducting tubes adjacent said division wall in each of said adjacent furnaces, means for securing said tubes of one furnace to said tubes of the adjacent furnace in such a manner that the tubes can move axially relative to each other, and means for supporting the division wall and said tubes at least in part adjacent the lower end thereof, said last named means being constructed and arranged to permit movement of the wall and the tubes resulting from expansion and contraction caused by operating temperatures in said adjacent furnaces.

3. Fluid heating apparatus comprising a setting, fluid heating tubes in the setting, a plurality of furnaces in the setting, means for firing each furnace, a division wall between adjacent furnaces, fluid conducting tubes adjacent said division wall in each of said adjacent furnaces, means for securing said tubes of one furnace to said tubes of the adjacent furnace in such a manner that the tubes can move axially relative to each other, and means for supporting the division wall and said tubes at least in part adjacent the lower end thereof, said last named

means being constructed and arranged to permit relative movement of the wall and the tubes resulting from expansion and contraction caused by different operating temperatures in said adjacent furnaces.

4. Fluid heating apparatus comprising a setting, fluid heating tubes in the setting, a plurality of furnaces in the setting, means for firing each furnace, means for separating the furnaces including rows of fluid conducting tubes, portions 10 of said tubes of one row being vertically inclined in one direction, and portions of said tubes of another row being vertically inclined in an opposite direction to provide at least in part adjacent bottom members for the furnaces sloping in opposite directions, and means for supporting said separating means at least in part adjacent said sloping bottom members and constructed and arranged to permit movement of the tubes of said rows resulting from expansion and contraction 20 caused by operating temperatures in said furnaces.

5. Fluid heating apparatus comprising a setting, fluid heating tubes in the setting, a plurality of furnaces in the setting, means for firing each furnace, means for separating the furnaces including rows of fluid conducting tubes, portions of said tubes of one row being vertically inclined in one direction and portions of said tubes of another row being vertically inclined in an opposite direction to provide at least in part adjacent bottom members for the furnaces sloping in opposite directions, means for supporting said furnace separating means and said furnace bottom members adjacent said members including 25 resilient means, and means for transmitting relative movement of said tubes resulting from expansion and contraction caused by operating temperatures in said furnaces to said resilient means.

6. Fluid heating apparatus comprising a setting, fluid heating tubes in the setting, a plurality of furnaces in the setting, means for firing each furnace, means for separating the furnaces including rows of fluid conducting tubes, portions of said tubes of one row being vertically inclined in one direction and portions of said tubes of another row being vertically inclined in an opposite direction to provide at least in part sloping bottoms for the furnaces, enclosing means associated with each of said sloping bottoms, means extending between said enclosing means and pivotally connected thereto, resilient means, means for supporting the resilient means, and means for pivotally connecting the resilient means to said means extending between said enclosing means.

7. Fluid heating apparatus comprising a setting, fluid heating tubes in the setting, a plurality of furnaces in the setting, means for firing each furnace, means for separating the furnaces including rows of fluid conducting tubes, portions 60 of said tubes of one row being vertically inclined in one direction and portions of said tubes of another row being vertically inclined in an opposite direction to provide at least in part sloping bottoms for the furnaces, enclosing means associated with each of said sloping bottoms, at least one link extending between said enclosing means and pivotally connected thereto, at least one coil spring, means for supporting the spring, 65 and means for pivotally connecting the link and the spring.

8. Fluid heating apparatus comprising a setting, fluid heating tubes in the setting, a plurality of furnaces in the setting, means for firing each 70 furnace, means for separating the furnaces including rows of fluid conducting tubes, and

furnace, means for separating the furnaces including rows of fluid conducting tubes, portions of said tubes of one row being vertically inclined in one direction and portions of said tubes of another row being vertically inclined in an opposite direction to provide at least in part sloping bottoms for the furnaces, enclosing means associated with each of said sloping bottoms, at least one link extending between said enclosing means and pivotally connected thereto, at least one coil spring, means for supporting the spring, means for pivotally connecting the link and the spring, and means permitting relative movement between the enclosing means and the supporting means for the spring.

9. Fluid heating apparatus comprising a setting, fluid heating tubes in the setting, a plurality of furnaces in the setting, means for firing each furnace, means for separating the furnaces including rows of fluid conducting tubes, a header with which the upper ends of the tubes are connected, means for supporting the header whereby the tubes are suspended from the header, a header with which the lower ends of the tubes of each row of tubes are connected, means for independently and resiliently supporting each of said lower headers, and supporting means for said tubes positioned between the upper and lower ends of the tubes, said supporting means being independent of said header supporting means and constructed and arranged to permit relative movement of the tubes of said rows resulting from expansion and contraction caused by operating temperatures in said furnaces.

10. Fluid heating apparatus comprising a setting, fluid heating tubes in the setting, a plurality of furnaces in the setting, means for firing each furnace, means for separating the furnaces including rows of fluid conducting tubes, portions of said tubes of one row being vertically inclined in one direction and portions of said tubes of another row being vertically inclined in an opposite direction to provide at least in part sloping bottoms for the furnaces, a header with which the upper ends of the tubes are connected, means for supporting the header whereby the tubes are suspended from the header, a header with which the lower ends of the tubes of each row of tubes are connected, means for independently and resiliently supporting each of said lower headers, enclosing means associated with each of said sloping bottoms, a link extending between said enclosing means and pivotally connected thereto, a coil spring, means for supporting the spring, and means for pivotally connecting the link and the spring.

11. Fluid heating apparatus comprising a setting, fluid heating tubes in the setting, a plurality of furnaces in the setting, means for firing each furnace, means for separating the furnaces including rows of fluid conducting tubes, and means for securing the tubes of one row to the tubes of another row to permit relative axial movement thereof, said securing means comprising an apertured lug welded to each tube, the lugs on one row of tubes being disposed at a different elevation than the lugs on the tubes of said other row with the apertures in vertical alignment, and pins extending through the vertically aligned apertures.

12. Fluid heating apparatus comprising a setting, fluid heating tubes in the setting, a plurality of furnaces in the setting, means for firing each furnace, means for separating the furnaces including rows of fluid conducting tubes, and

means for securing the tubes of one row to the tubes of another row to permit relative axial movement thereof, said securing means comprising an apertured lug welded to each tube, the lugs on one row of tubes being disposed at a different elevation than the lugs on the tubes of said other row with the apertures in vertical alignment, tie members associated with the lugs on each row of tubes, the tie members having apertures in alignment with the lug apertures and extending transversely of a plurality of tubes with the joints between the tie members at one elevation being staggered with respect to the joints between the other tie members, and pins extending through the vertically aligned apertures in the lugs and tie members.

13. A furnace having walls and a vertically inclined floor, fluid conducting tubes for said inclined floor, and means for supporting the tubes on the floor to permit relative axial movement of the tubes with respect to the floor comprising a lug secured to each tube, a plurality of blocks in the floor disposed in spaced relationship and located to receive said lugs in the spaces between the blocks, and means for maintaining said blocks in position in the floor.

14. A furnace having walls and a vertically inclined floor, fluid conducting tubes for said inclined floor, and means for supporting the tubes on the floor to permit relative axial movement of the tubes with respect to the floor comprising a lug secured to each tube, a plurality of blocks in the floor disposed in spaced relationship and located to receive said lugs in the spaces between the blocks, each block having an extension, and means engaging said block extensions for maintaining said blocks in position in the floor.

15. A furnace having walls and a vertically inclined floor, fluid conducting tubes for said inclined floor, and means for supporting the tubes on the floor to permit relative axial movement of the tubes with respect to the floor comprising a lug secured to each tube, a plurality of blocks in the floor disposed in spaced relationship and located to receive said lugs in the spaces between the blocks, each block having an extension, and spaced channel members in engagement with opposite sides of said extensions for maintaining said blocks in position in the floor.

16. Fluid heating apparatus comprising a setting, fluid heating tubes in the setting, a plurality of furnaces in the setting, means for firing each furnace, means for separating the furnaces including rows of fluid conducting tubes, portions of said tubes of one row being vertically inclined in one direction, and portions of said tubes of another row being vertically inclined in an opposite direction to provide at least in part adjacent bottom members for the furnaces sloping in opposite directions, and means for supporting said separating means at least in part adjacent said sloping bottom members and constructed and arranged to permit movement of the tubes of said rows in relation to one another resulting from expansion and contraction caused by operating temperatures in said furnaces.

17. Fluid heating apparatus comprising a setting, fluid heating tubes in the setting, a plurality of furnaces in the setting, means for firing each furnace, a division wall between adjacent furnaces, fluid conducting tubes adjacent said division wall in each of said adjacent furnaces, means for securing said tubes of one furnace to said tubes of the adjacent furnace in a manner to permit relative axial movement between said

5 fluid conducting tubes and prevent transverse movement of the tubes of each row and lateral movement of said rows in relation to each other, and means for supporting the division wall and said tubes at least in part adjacent the lower end thereof, said last named means being constructed and arranged to permit movement of the wall and the tubes resulting from expansion and contraction caused by operating temperatures in said adjacent furnaces.

18. Fluid heating apparatus comprising a setting, fluid heating tubes in the setting, a plurality of furnaces in the setting, means for firing each furnace, a division wall between adjacent furnaces, fluid conducting tubes adjacent said division wall in each of said adjacent furnaces, means for securing said tubes of one furnace to said tubes of the adjacent furnace in a manner to permit relative axial movement between said fluid conducting tubes and prevent transverse movement of the tubes of each row and lateral movement of said rows in relation to each other, and means for supporting the division wall and said tubes at least in part adjacent the lower end thereof, said last named means being constructed and arranged to permit relative movement of the wall and the tubes resulting from expansion and contraction caused by different operating temperatures in said adjacent furnaces.

30 19. Fluid heating apparatus comprising a setting, fluid heating tubes in the setting, a plurality of furnaces in the setting, means for firing each furnace, a division wall between adjacent furnaces, the division wall at the bottom thereof being divided, one portion thereof being vertically inclined in one direction and another portion thereof being vertically inclined in an opposite direction, fluid conducting tubes adjacent said division wall and the vertically inclined portions thereof, means for supporting the tubes on said inclined portions of the wall to permit relative axial movement of the tubes in respect to the inclined portions comprising a lug secured to each tube, a plurality of blocks in the inclined portions of the division wall disposed in spaced relationship and located to receive said lugs in the spaces between the blocks, means for maintaining said blocks in position in the inclined portions, and means for supporting said division wall and said tubes at least in part adjacent the lower end thereof, said last named means being constructed and arranged to permit relative movement of the wall and the tubes resulting from expansion and contraction caused by different operating temperatures in said adjacent furnaces.

55 20. Fluid heating apparatus comprising a setting, fluid heating tubes in the setting, a plurality of furnaces in the setting, means for firing each furnace, means for separating the furnaces including rows of fluid conducting tubes, means for securing said tubes of one furnace to said tubes of the adjacent furnace in a manner to permit relative axial movement between said fluid conducting tubes and prevent transverse movement of each row and lateral movement of said rows in relation to each other, and means for supporting said separating means at least in part adjacent the lower end thereof, said last mentioned means being constructed and arranged to permit relative movement of the tubes of said rows resulting from expansion and contraction caused by different operating temperatures in said furnaces.
